US00D887828S

(12) **United States Design Patent** (10) Patent No.: **US D887,828 S**
(45) Date of Patent: ** Jun. 23, 2020

(54) **PACKAGING**

- (71) Applicant: **Apple Inc.**, Cupertino, CA (US)
- (72) Inventors: **Francesca Amor Delle Cese**, San Francisco, CA (US); **Lorraine Y. Tang**, San Francisco, CA (US); **Bhautik H. Mehta**, Mountain View, CA (US); **Mark T. Uyeda**, Campbell, CA (US); **Alissa Anderson**, San Francisco, CA (US); **Jonathan Berk**, Mountain View, CA (US); **Margaret Madigan Burke**, Sunnyvale, CA (US); **Jack Wanderman**, San Francisco, CA (US); **Kevin Scott Fetterman**, Los Altos, CA (US)
- (73) Assignee: **Apple Inc.**, Cupertino, CA (US)
- (**) Term: **15 Years**
- (21) Appl. No.: **29/681,908**
- (22) Filed: **Feb. 28, 2019**

Related U.S. Application Data

- (63) Continuation of application No. 29/643,333, filed on Apr. 6, 2018, now Pat. No. Des. 842,091, which is a continuation of application No. 29/588,231, filed on Dec. 19, 2016, now Pat. No. Des. 814,919, which is a continuation of application No. 29/519,936, filed on Mar. 9, 2015, now Pat. No. Des. 774,899, which is a continuation-in-part of application No. 29/519,821, filed on Mar. 9, 2015, now Pat. No. Des. 779,932.

CLAIM

The ornamental design for a packaging, as shown and described.

DESCRIPTION

FIG. 1 is a top front exploded perspective view of packaging showing the claimed design;

FIG. 2 is a top front perspective view of the sleeve of FIG. 1;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top front perspective view of the accessory holder insert of FIG. 1;

FIG. 10 is a front view thereof;

FIG. 11 is a rear view thereof;

FIG. 12 is a left side view thereof;

FIG. 13 is a right side view thereof;

FIG. 14 is a top view thereof; and,

FIG. 15 is a bottom view thereof.

The broken lines in the figures show portions of the packaging that form no part of the claimed design.

1 Claim, 8 Drawing Sheets
